UNITED STATES PATENT OFFICE.

MAX W. HENIUS AND JOHN HERROLD, OF NEW YORK, N. Y.; SAID HERROLD ASSIGNOR TO SAID HENIUS.

METAL-BENDING MACHINE.

SPECIFICATION forming part of Letters Patent No. 643,353, dated February 13, 1900.

Application filed April 10, 1899. Serial No. 712,373. (No model.)

To all whom it may concern:

Be it known that we, MAX W. HENIUS and JOHN HERROLD, citizens of the United States, and residents of New York, in the county of 5 Kings and State of New York, have invented a new and useful Improvement in Metal-Bending Machines, of which the following is a specification.

Our invention relates to an improvement 10 in metal-bending machines; and it consists more particularly in a new machine for bending strips of sheet metal—such, for instance, as corset-steels.

The objects of our invention are to provide 15 a machine of the above character in which the corset-steels will be very rapidly bent, in which the bending of each steel may be started at any desired point, and in which any desired bend may be imparted to the steel.

20 A further object is to provide means for timing the admission of the steels into the machine, so that one steel will not be permitted to overlap the next preceding steel.

A practical embodiment of our invention 25 is represented in the accompanying drawings, in which—

Figure 1 is a view in side elevation of the machine. Fig. 2 is a top plan view of the same. Fig. 3 is a vertical section from front 30 to rear through the machine. Fig. 4 is a top plan view of the machine with the hopper for feeding the steels into the machine removed. Fig. 5 is a front view of the machine. Fig. 6 is a rear view of the same. Fig. 7 is a plan 35 view with the top of the frame removed. Fig. 8 is a vertical section from front to rear through the upper portion of the machine, the parts being in the position which they assume when forming a bend in the steel; and Fig. 9 represents partial front and side views 40 of one of the steels after it has been bent.

The framework of the machine comprises a base A, side frames a a' , rigidly spaced apart by cross-bars a^2 , and a top a^3 . The top a^3 has a steel-receiving slot or opening a^4 therethrough.

A pair of bending-rolls B and C are carried by shafts b and c , mounted to rotate in suitable bearings in the side frames a a' , the 45 bearings for the front-roll shaft b being sta-

tionary and the bearings for the rear-roll shaft c having a limited sliding movement toward and away from the front of the machine. These rolls B and C are located near the top of the machine beneath the steel-receiving 55 opening a^4 .

An auxiliary frame is hinged within the casing on the shaft c , which frame comprises a pair of side plates D D' and a cross-bar d , connecting their lower ends. A bending-roll 60 E is carried by a rotary shaft e , mounted in stationary bearings in the side plates D D' of the auxiliary frame, the said shaft being located a short distance below the shaft c of the rear roll. 65

A rotary cam-shaft F is mounted in adjustable bearings in the side frames a a' , each of the said bearings of the shaft F being capable of adjustment by means of a pair of adjusting-screws f^1 , leading from the front of the 70 machine into engagement with one side of the bearing and from the back of the machine into engagement with the other side of the bearing. The shaft F is provided on one end exterior to the side frame with a drive-pulley 75 f^2 , by means of which the shaft may be driven from a source of power. (Not shown.)

The rotary movement of the shaft F is imparted to the front-roll shaft b by a gear-wheel f^3 on the shaft F between the drive-pulley f^2 and the side frame a , intermediate gear-wheels G G' , mounted on stub-axles g g' , and a gear-wheel b^1 , carried by the end of the said shaft b . Rotary movement is imparted from the front-roll shaft b to the rear-roll 85 shaft c , whether the rolls are closer to or farther from each other, by a gear-wheel b^2 on the shaft b and a gear-wheel c' on the shaft c , both of which gears are provided with extra long teeth, so as to permit a considerable 90 movement toward and away from each other without being disconnected. Rotary movement is imparted to the lower roll-shaft e by means of a gear-wheel e' on the shaft e in a different plane from the gear-wheels c' and 95 an intermediate wide gear-wheel H, carried by a shaft h , mounted in the side plates D D' of the auxiliary swinging frame.

A swinging movement is imparted to the auxiliary frame by a pair of cams f^4 f^5 , car- 100

ried by the shaft F in position to engage the rear edges of the side plates D D'. A spring d' leads from the cross-bar d of the swinging frame to a bracket d², carried by one of the 5 cross-bars a².

The pivot-shaft c of the swinging frame is caused to slide toward and away from the front of the machine at predetermined intervals during the swinging movement of the 10 auxiliary frame to alternately permit the rolls B and C to engage the rear portion of one steel to bend it and to permit the advance portion of the next succeeding steel to pass freely between the said rolls. This movement is accomplished by providing stop-pins 15 II', projecting inwardly from the side frames a a' in position to engage the front edges of the side plates D D' at the top of the swinging frame, and a cross-bar I², mounted in 20 sliding bearings in the side frames a a', which cross-bar is caused to engage the rear edges of the side plates D D'. This cross-bar is adjusted by screws i, extending from the back 25 of the side frames into engagement with the sliding bearings of the said cross-bar.

By adjusting the bar I² the greatest distance between the rolls B and C may be regulated to suit steels of different thicknesses, and by adjusting the bearings of the shaft F 30 the amount of bend to be imparted to the steels may also be regulated.

A funnel-shaped hopper J is mounted on the top a³ of the machine, the discharge-opening of the said hopper being arranged in line 35 with the steel-receiving opening a¹ in the top of the casing. A gate K is fitted to slide between the discharge-opening in the hopper J and the opening a⁴, which gate is provided with an opening k, arranged to open communication between the mouth of the hopper J and the opening a⁴ when the gate is slid forwardly and to close communication between the hopper and the opening a⁴ when the gate is slid rearwardly. This gate is operated by 40 a rocking lever L, having one arm engaged with the gate and its other arm engaged by a cam f⁶, carried by the shaft F. The rocking lever L is held in engagement with the cam f⁶ by a retracting-spring l, leading from 45 the lower arm of the lever to one of the cross-bars a² of the frame.

An adjustable stop is located at the front of the machine a considerable distance below the bending-rolls. This stop comprises a table M, having downwardly-extended branches m m, which are secured to the side frames a a' by bolts m³, which pass through elongated slots m² in the said ears. This stop may be adjusted toward and away from the bending- 55 rolls, so as to determine the point on the steel which is inserted within the machine at which the bend shall be started.

An adjustable discharge-plate N is carried by the auxiliary swinging frame, which plate 60 is provided with ears n n', having vertically-elongated slots n², through which pass clamping-bolts n³ for clamping the discharge-plate

in any desired vertical adjustment. This discharge-plate N is fitted to engage the advance or lower end of the steel as the frame 70 is swung forwardly and positively swing the said steel outwardly away from the machine as it is being bent, thus preventing any tendency on the part of the steel to stick in its first position within the machine.

In operation the steel to be bent is dropped into the hopper J. The gate K will be slid to the limit of its forward movement and the rolls B and C at the same time moved a distance apart sufficient to permit the steel to 80 fall freely until its lower end rests upon the stop M. The auxiliary frame is then swung forward. This movement will bring the two rolls B and C into contact with the opposite faces of the steel and will bring the roll E 85 into engagement with the inner face of the steel and bend it partially around the roll B, the discharge-plate N at the same time positively freeing the lower end of the steel from the adjustable stop M. Before the steel is 90 entirely withdrawn by the rolls B and C from the hopper J the cam f⁶ will have released the lever L, and the spring l will cause the lever to pull the gate K rearwardly against the outer face of the steel, so that the moment that the rear end or top of the steel leaves the opening in the gate the gate will 95 close and will not permit the next succeeding steel to be fed into the machine until the proper time.

The machine as above described is capable of forming bends in metal strips in a very rapid and efficient manner and at the same time is capable of forming the bend at any desired portion in the strip and making the 100 bend greater or less, as may be desired.

The term "corset-steel" which we have herein used is intended to cover corset-stiffenings of any metal, and it is also to be understood that the machine can be advantageously employed for bending metallic strips for other purposes, if so desired.

By forming the hopper J funnel-shaped the steel may be freely dropped into the hopper and will not be confined closely therein except at the discharge end of the same.

It is evident that slight changes might be resorted to in the form and arrangement of the several parts without departing from the spirit and scope of this invention. Hence we 120 do not wish to limit ourselves strictly to the structure herein set forth; but

What we claim is—

1. In a machine for bending corset-steels, bending-rolls, an adjustable stop, means for 125 feeding the steel between the rolls into engagement with the stop and means for operating the rolls to form a bend in the steel, substantially as set forth.

2. In a machine for bending corset-steels, a 130 pair of bending-rolls, a swinging frame hinged on one of the bending-roll shafts, a third bending-roll mounted in said frame, means for feeding the steels between the bending-rolls

- and means for swinging the frame for forming bends in the steels, substantially as set forth.
3. In a machine for bending corset-steels, a pair of bending-rolls, a swinging frame hinged on the shaft of one of the bending-rolls, a third bending-roll mounted in the said swinging frame, means for feeding the steels between the bending-rolls and a rotary cam arranged to swing the frame to form bends in the steels, substantially as set forth.
4. In a machine for bending corset-steels, bending-rolls, a stop carried by the machine, means for feeding the steels between the rolls into engagement with the stop, a swinging frame, means for operating it for forming bends in the steels and a discharge-plate carried by the swinging frame in position to engage the advance ends of the steels adjacent to the stop for swinging them outwardly away from the machine, substantially as set forth.
5. In a machine for bending corset-steels, a pair of bending-rolls, a swinging frame hinged on one of the bending-roll shafts, a third bending-roll, mounted in the said frame, a rotary cam-shaft, a cam thereon for operating the frame, a hopper for containing a steel, means for opening and closing the mouth of the hopper comprising a sliding gate and a rocking lever having one arm engaged with the gate and the other with a cam on the cam-shaft, substantially as set forth.
6. In a machine for bending corset-steels, means for feeding steels into the machine, a bending-roll mounted in stationary bearings in the frame, a second bending-roll mounted in sliding bearings in the frame, a swinging frame, hinged on the shaft of the second-named bending-roll, a third bending-roll mounted in the frame, a rotary shaft for swinging the frame and means for moving the second-named roll toward and away from the first-named roll at predetermined intervals for causing the said rolls to alternately permit the free passage of the steel therethrough and to engage the said steel, substantially as set forth.

7. In a machine for bending corset-steels, a bending-roll mounted in stationary bearings in the frame, a second bending-roll mounted in sliding bearings in the frame, a swinging frame hinged on the shaft of the second-named bending-roll, means for swinging the frame and means for sliding the second-named roll toward and away from the first-named roll comprising stops arranged to engage the front and rear of the swinging frame fitted to act in conjunction with the means for swinging the said frame, substantially as set forth.
8. In a machine for bending corset-steels, a bending-roll mounted in stationary bearings in the frame, a second bending-roll mounted in sliding bearings in the frame, a spring-actuated swinging frame hinged on the shaft of the second-named bending-roll, means for swinging the frame and means for sliding the second-named roll toward and away from the first-named roll comprising a stationary stop engaging the front of the swinging frame, and an adjustable stop engaging the rear of the said frame, the said stops being fitted to coact with the means for swinging the frame, substantially as set forth.

9. In a machine for bending corset-steels, a bending-roll mounted in stationary bearings in the frame, a second roll mounted in sliding bearings in the frame, a swinging frame hinged on the shaft of the second-named bending-roll, a third bending-roll mounted in the said swinging frame, a rotary cam for swinging the said frame and means for adjusting the said shaft toward and away from the swinging frame to regulate the amount of bend in the steels, substantially as set forth.

In testimony that we claim the foregoing as our invention we have signed our names, in presence of two witnesses, this 28th day of March, 1899.

MAX W. HENIUS.
JOHN HERROLD.
